(57) CLAIM

The ornamental design for a couch saver pet bed, as shown and described.

DESCRIPTION

FIG. 1 is a front view of the couch saver pet bed showing my new design;

FIG. 2 is a rear elevational view thereof;

FIG. 3 is a top plan view thereof;

FIG. 4 is a bottom plan view thereof; and,

FIG. 5 is a perspective view thereof.

The broken lines in FIGS. 1-5 depict portions of the couch saver pet bed that form no part of the claim.
